UNITED STATES PATENT OFFICE.

MARCUS S. CLARKE, OF HOUSTON, TEXAS.

HYDROCARBON-BURNER.

2,017,624.

Specification of Letters Patent. Patented Feb. 13, 1912.

Application filed March 9, 1911. Serial No. 613,269.

To all whom it may concern:

Be it known that I, MARCUS S. CLARKE, a citizen of the United States, residing at Houston, in the county of Harris and State of Texas, have invented certain new and useful improvements in Hydrocarbon-Burners, of which the following is a specification.

My invention relates to new and useful improvements in hydrocarbon burners.

The object of the invention is to provide a device of the character described so constructed as to admit a forced draft of steam or air which surrounds the nozzle of the fuel passage way and creates a suction, thereby assisting the flow of fuel from the fuel reservoir through the fuel passageway, the fuel being thoroughly mixed with said air or steam in a mixing chamber into which the said nozzle discharges, all the air being admitted for combustion through a choked or tapering mixing chamber and the fuel being delivered from it into the fire box in finely atomized form.

Another object of the invention resides in the provision of a fuel passageway which is provided with a slip joint, connecting the parts thereof, one of the parts of said passageway being slidable upon the other part and being held in position by means of a coil spring, thus providing an easy method of fitting the atomized, and for an easy removal of the parts.

Another feature of the invention resides in the provision of an air inlet communicating with the anterior of the heating chamber and also with the fuel inlet, through which heated air is inducted into the fuel passageway, which heats said fuel and assists in the perfect atomization thereof.

Still further features resides in the provision of a nozzle having a rounded nose over which a blow-back cup fits, for cleansing the burner.

With the above and other objects in view, which will be set forth more in detail, hereinafter, my invention has particular relation to certain novel features of construction, operation, and arrangement of parts, an example of which is given in this specification and illustrated in the accompanying drawings, wherein:

Figure 1 is a side elevation, partially in

section, of the burner. Fig. 2 is a sectional side elevation of the blow-back cup used in cleansing the same. Fig. 3 is a side elevation of the burner shown in its proper relation to the furnace in connection with which the same is to be used. Fig. 4 is a sectional plan view thereof taken on the line *a—a* of Fig. 3, and Fig. 5 is a sectional end view thereof taken on the line *b—b* of Fig. 3 looking toward the burner nozzle.

Referring now more particularly to the drawings, wherein like numerals of reference designate similar parts in each of the figures, the numeral 6 refers to a draft nozzle which is substantially cylindrical in shape and which is screwed onto the nipple 7, which projects from the collar 7' and is integral therewith. This collar is screwed onto the pipe section 8. Within this nozzle, and integral with the nipple, is the stem 8', forming a portion of the fuel passageway. This stem alines with an internal passageway of nipple 7 and extends toward the nose of the nozzle 6 and in length is about one-half the length of said nozzle. The nose 9 of nozzle 6 is reduced and tapers toward its end and is offset relative to the body of said nozzle so as to form an abrupt shoulder 10, connecting said nose 9 and the body of the nozzle.

The numeral 11 refers to a sleeve which fits over the free end of stem 8', so as to form a slip joint and this sleeve is elongated into a tube 12, which alines with stem 8' and extends within the nose 9 to the end thereof and is provided with a plurality of radiating arms 13 whose free ends rest against the inner side of discharge nose 9 and hold the tube 12 centered relatively to the nozzle, the stem 8' and tube 12, together with the connecting sleeve 11 forming a continuous fuel passageway through the draft nozzle 6.

The numeral 14 refers to a coil spring which is interposed between sleeve 11 and nipple 7 and which forms a resilient cushion for said sleeve and normally holds the tube 12 extended completely through nose 9, but which permits said tube to be forced back thus enlarging the passageway between the discharge end of said tube and said nozzle 6.

The draft of steam or air is admitted into nozzle 6 through force pipe 15 and is driven

through the nose 9, passing around the nozzle of tube 12 and by reason of the taper or choke of nose 9, creating a suction through the fuel passageway. The fuel is admitted 5 under pressure from a suitable fuel reservoir (not shown) through pipe 16, which is controlled by a suitable gate valve 17, and passes through tubes 8' and 12 and is forced through the passageway 18 of the 10 furnace wall 19 into the mixing chamber 20 in which it is thoroughly atomized and mixed with the steam or air in said mixing chamber, and ignited and from which it is driven, by the force of said draft against 15 the wall 21, of the furnace.

The passageway 18, and the mixing chamber 20 taper from their receiving to their discharge ends and align with each other as well as with the burner, as shown in Fig. 20. The mixing chamber 20 is provided with an air inlet 32, underneath, through which additional air may be supplied and the tapering contour of this chamber is such as to create a suction therethrough and cause a 25 complete mixture of the air and fuel therein.

The numeral 22 refers to an auxiliary pipe which communicates with the interior of the furnace and extends through the wall 19 thereof and communicates, also, with the 30 fuel passageway and is provided for the purpose of introducing hot gases from the furnace into the fuel passageway which heats and mixes with the fuel and thus assists in the atomization of said fuel. This 35 auxiliary pipe 22 is controlled by a gate valve 23 by means of which the passage of the gases therethrough may be regulated, and when the burner is in operation this valve is partly closed so that only a limited 40 supply of gas enters the fuel pipe.

The nose, or discharge end 9, of the burner is completely surrounded with a funnel shaped hood 24 which is supported thereon by means of the ring 25, screwed 45 onto said discharge end 9, and radiating arms 26 extending from said ring and secured to said hood. The shoulder 10, of nozzle 6 is provided with a plurality of openings 27, through which jets of the atomizing fluid are driven within the surrounding 50 hood 24 thereby creating a suction through said hood and around the nose 9, which draws in an additional supply of air which is mixed with the fuel as it leaves the mouth 55 of the nozzle.

The numeral 27' refers to a blow-back cup whose interior conforms to the rounded end of nose 9 and which is designed to be placed thereover when it is desired to clean the 60 burner or unstop either of the inlet pipes leading thereto. The bottom of this cup carries a projecting cross 28 which engages against the free end of tube 12 and forces the same back, depressing the coil spring 14, 65 while the cup proper rests against the nose

9. In case it is desired to cleanse the burner of any obstructions which may have collected in either passage way thereof the plug 29 is removed from feed pipe 16 and when the nozzle is closed by cup 27' the atomizing fluid is driven through the fuel passageway and escapes through the opening in the feed pipe left by the removal of plug 29. Both gate valves 17 and 23, should be closed when it is desired to thus cleanse the burner. 70 When either of the pipes, 16 or 22, becomes clogged, the gate valve of said clogged pipe may be opened, and the other gate valve closed and plug 29 screwed into place. The cup 27' is then applied over the mouth of nozzle 6 and the atomizing fluid will be driven through the clogged pipe, thus unclogging the same. The bottom of cup 27' is provided with a socket 30 in which a suitable rod or bar may be placed and secured by set screw 31, and a handle for said cup thus provided. The cup may then be applied to the burner nozzle and the burner pipes cleansed, as above described. 75

What I claim is:—

1. A device of the character described including a nozzle having a tapering free end, and a fuel pipe formed of telescoping sections extending therethrough, a fuel supply inlet and an inlet for furnace gases each 90 communicating with said fuel pipe and supplying fuel and furnace gases thereto and a resilient seat surrounding one of said telescoping pipe sections upon which the other 95 of said sections rests. 100

2. A device of the character described including a nozzle having a tapering free end and a telescoping tube extending therethrough, said tube being composed of two sections, one of which is immovable with respect to the nozzle and the other of which is united to the immovable section by means of a slip joint, the discharge end of the movable section being flush with the discharge end of the nozzle, a resilient cushion 110 against which said movable section rests, a fuel supply inlet and an inlet for furnace gases communicating with said tube and supplying fuel and furnace gases thereto, and an inlet for spraying fluid communicating 115 with the nozzle. 120

3. A device of the character described including a suitable burner nozzle and a telescoping fuel conducting tube extending therethrough, said tube being composed of two sections united by a slip joint, a fuel supply inlet and an inlet for furnace gases communicating with said tube, an inlet for spraying fluid communicating with said nozzle, a hood surrounding the discharge end of said nozzle and forming an air passageway between the hood and the discharge end of the nozzle, said nozzle being provided with a plurality of vents which discharge jets of the spraying fluid from 125 130

- the nozzle within the hood and create a suction between said hood and nozzle.
4. A device of the character described including a nozzle having a reduced free end, a fuel supply tube extending therethrough, said tube being composed of two sections united by a slip joint, a coil spring arranged to serve as a seat for one section of the tube and hold the free end of the same flush with the free end of the nozzle, a fuel supply inlet and an inlet for furnace gases communicating with said tube, and an inlet for spraying fluid communicating with said nozzle.
5. A device of the character described including a nozzle and a detachable hood surrounding the free end and conforming to the shape thereof and providing an air passage between said hood and said nozzle end, a fuel pipe formed of telescoping sections united by a slip joint, a resilient member surrounding one of said sections and forming a seat for the other of said sections, and a fuel supply inlet and an inlet for furnace gases each communicating with said fuel pipe and supplying fuel and furnace gases thereto.
6. A device of the character described including a nozzle having a tapering free end and a detachable hood surrounding said free end and conforming to the shape thereof and providing an air passage between said hood and said nozzle end, said nozzle being provided also with a plurality of vents communicating with the interior of the nozzle and also with said air passage between said hood and nozzle, a fuel pipe formed of telescoping sections extending through said nozzle, a resilient member surrounding one of said sections and forming a seat for the other of said sections, a fuel supply inlet and an inlet for furnace gases each communicating with said fuel pipe and supplying fuel and furnace gases thereto, and means for controlling the flow of fuel and furnace gases through said inlets.
7. A device of the character described including a nozzle having a tapering free end, and a fuel pipe formed of telescoping sections extending therethrough, a fuel supply inlet and an inlet for furnace gases each communicating with said fuel pipe and supplying fuel and furnace gases thereto, a resilient seat surrounding one of said telescoping pipe sections upon which the other of said sections rests, and an inlet for spraying fluid entering said nozzle for conducting a draft into the same and around said fuel pipe.
8. A device of the character described including a nozzle having a tapering free end, and a fuel pipe formed of telescoping sections extending therethrough, a fuel supply inlet communicating with said fuel pipe and supplying fuel thereto and a resilient seat surrounding one of said telescoping pipe sections upon which the other of said sections rests.
9. A device of the character described including a nozzle having a tapering free end and a detachable hood surrounding said free end and conforming to the shape thereof and providing an air passage between said hood and said nozzle end, a fuel pipe formed of telescoping sections united by a slip joint, a resilient member surrounding one of said sections and forming a seat for the other of said sections, and a fuel supply inlet communicating with said fuel pipe and supplying fuel thereto.
10. A device of the character described including a nozzle having a tapering free end and a detachable hood surrounding said free end and conforming to the shape thereof and providing an air passage between said hood and said nozzle end, said nozzle being provided also with a plurality of vents communicating with the interior of said nozzle and also with said air passage, a fuel pipe formed of telescoping sections extending through said nozzle, a resilient member surrounding one of said sections and forming a seat for the other of said sections, a fuel supply inlet communicating with said fuel pipe and supplying fuel thereto, and means for controlling the flow of fuel through said inlet.
11. A device of the character described including a nozzle and a fuel pipe formed of telescoping sections extending therethrough, a fuel supply inlet communicating with said fuel pipe and supplying fuel thereto and a resilient seat surrounding one of said telescoping pipe sections, upon which the other of said sections rests.
12. A device of the character described including a nozzle, a detachable hood surrounding the free end thereof and conforming to the shape of said free end and providing an air passageway between said hood and said nozzle end, said nozzle being provided also with a plurality of vents communicating with the interior of the nozzle and also with said air passageway, a fuel pipe extending length-wise through said nozzle, a fuel supply inlet communicating with said fuel pipe and supplying fuel thereto and an inlet for furnace gases also communicating with said fuel pipe.
13. A device of the character described including a nozzle having a tapering free end and arranged to discharge into a combustion chamber, a detachable hood surrounding said free end and conforming to the shape thereof and forming an air passageway between said hood and said nozzle end, said nozzle being provided also with a plurality of vents communicating with the interior of the nozzle and also with the air

4
passageway, a fuel pipe extending through the nozzle, a fuel supply inlet communicating with said pipe and supplying fuel thereto and an inlet for furnace gases leading from said combustion chamber and communicating with said fuel pipe and supplying furnace gases thereto.

In testimony whereof I have signed my name to this specification in the presence of two subscribing witnesses.

MARCUS S. CLARKE.
